UNITED STATES PATENT OFFICE.

GEORGE W. MCGILL, OF NEW YORK, N. Y.

DESIGN FOR A PAPER-FASTENER.

SPECIFICATION forming part of Design No. 21,099, dated October 6, 1891.

Application filed September 12, 1891. Serial No. 405,542. Term of patent 14 years.

To all whom it may concern:

Be it known that I, GEORGE W. MCGILL, a citizen of the United States, residing at Riverdale, New York, in the county of New York and State of New York, have invented and produced a new and original Design for Paper and other Fasteners, of which the following is a specification.

This design has for its object to provide a novel and ornamental paper or other fastener; and it consists in a fastener having an oblong head provided with beveled sides and a flattened lower surface, from the center of which extend two superimposed prongs.

The design is illustrated by the accompanying drawings, in which—

Figure 1 is a perspective view looking at the upper surface of the fastener. Fig. 2 is a similar view looking at the lower side of the same, and Fig. 3 is a top plan view.

In the drawings, the numeral 1 indicates

the oblong head, having beveled sides 2 and a flattened lower side 3, from the center of which extend two flat rectangular superimposed prongs 4 and 5 of different length. ²⁵

The design provides a novel and ornamental paper or other fastener, which presents a striking and characteristic appearance.

What I claim is—

The design for a fastener having an oblong head provided with beveled sides and a flattened lower surface, from the center of which extend two superimposed prongs, substantially as shown and described. ³⁰

In testimony whereof I have hereunto set my hand and affixed my seal in presence of two subscribing witnesses.

GEORGE W. MCGILL. [L. S.]
